UNITED STATES PATENT OFFICE.

CHARLES H. LITTLE, OF EAST CLEVELAND, OHIO.

RULER.

1,274,292.

Specification of Letters Patent. Patented July 30, 1918.

Application filed May 26, 1913. Serial No. 769,781.

To all whom it may concern:

Be it known that I, CHARLES H. LITTLE, a citizen of the United States, residing at East Cleveland, in the county of Cuyahoga and State of Ohio, have invented a certain new and useful Improvement in Rulers, of which the following is a full, clear, and exact description.

This invention relates to improvements in rulers, such as forms the subject matter of my prior application for rulers, Serial No. 652,918, October 5th, 1911, the present invention being in the nature of an improvement over certain features embodied in the ruler construction disclosed in said application.

The ruler constructed in accordance with my prior invention comprises a body which is formed into tubular shape from a thin strip of sheet metal. This body, unlike the body of a wooden ruler, will not warp out of shape, but at the same time, it is light in weight, possesses rigidity and stiffness, and has edges which are straight and parallel, 25 and which in the case of the scale are thin, as is desirable for close accurate work. In addition to the above mentioned important features, the ruler is provided along its edges with a strongly adhering medium, in 30 the form of strips, which are cemented to the body, and in which graduations and characters may be cut.

The present invention in one of its aspects resides in certain improvements in the construction of the ruler body, one of the objects being to provide more effective means for preventing lateral springing or spreading of the ruler body, and distortion of the side edges from true parallelism. Another 40 object is to provide a closure for the ends of the tubular ruler body which does away with the necessity for closing inserts and which provides a strong, neat and otherwise desirable end construction.

45 A further object is to provide an improvement in the medium which is applied to the ruler body, for the cut graduations and characters, and as a protective coating and permanent finish.

50 In the accompanying sheets of drawings, wherein I have shown my invention applied to a scale, Figure 1 is a top plan view of the scale with parts removed; Fig. 2 is an enlarged transverse sectional view, sub-

stantially along the line 2—2 of Fig. 1, parts 55 on the interior of the ruler body being omitted; Fig. 3 is a bottom view of an end portion of the scale; Figs. 4 and 5 are transverse sectional views on a slightly enlarged scale, substantially along the line 4—4 and 60 2—2, respectively, Fig. 4 showing the interior parts not shown in Fig. 2; and Fig. 6 is an enlarged longitudinal sectional view of one end of the scale substantially along the line 6—6 of Fig. 1. 65

The scale is provided with a body which is formed into tubular shape from a thin strip of sheet metal, and, except for certain improvements to be described, which have been rendered in the construction of the 70 body, the latter is of the same shape and form as the ruler body shown in my prior application, previously referred to. The body includes a flat top portion a , and beveled or inclined portions a' which extend 75 from shoulders or offsets a^2 along the edges of the portion a to the edges of the body. The bottom of the ruler body is formed by bending side portions a^3 of the strip inwardly at acute angles to the portions a' , 80 these portions a^3 extending inwardly to substantially the center plane of the body. The edge portions of the strip are bent upwardly into the interior of the ruler body and extend between the top and bottom 85 walls so as to constitute an integral internal bracing rib. The side edges of the body are formed by the bending process straight and parallel, and the edges are slightly rounded and quite thin, as will be seen from Fig. 2. 90

As in my prior construction, the two parts a^3 of the bottom wall of the ruler body are mechanically fastened together at intervals, the mechanical fastening means consisting of pairs of concentric bushings which are arranged along the center line of the ruler body, the central bracing rib a^4 being notched or cut away at the proper points to accommodate the bushings. As will be observed, each of these pairs or sets of bushings includes an outer bushing b into which portions of both parts a^3 of the bottom wall are upwardly bent, and an inner bushing b' which is driven tightly in place from the lower side of the ruler body. Not only do 100 these bushings serve to mechanically fasten together the adjacent parts of the lower side of the ruler body, but by using inner

bushings which are threaded on the interior, said bushings constitute very effective anchorages for screws *c* which secure to the top of the ruler body, chuck plates *d* which 5 adapt the ruler for use with universal drafting machines.

One of the important features of the present construction resides in an interlock for the edge portions of the strip which form 10 the inner bracing rib *a*⁴. In my prior construction shown in the application previously referred to, the edge portions of the strip are bent upwardly from the bottom wall, side by side, to the top wall and are 15 not interlocked.

In the present construction, the edge portions extend between the top and bottom walls, but each edge portion is doubled back upon itself so as to form trough shaped or 20 U-shaped folds *a*⁵ and *a*⁶, and the interlock is formed by inserting one folded part *a*⁵ into the other. These folded parts have a certain degree of spring, and are so formed that when one is inserted within the other, 25 the two interlocking portions grip each other tightly, with the result that the portions *a*³ of the bottom wall are united or held together from one end of the ruler body to the other, and this interlocking as 30 sists the bushings in holding together the parts of the ruler body, and particularly, it overcomes all tendency for lateral spreading or springing of the portions of the bottom wall located between the sets of bushings, and thus maintains the outer working 35 edges in true parallelism.

It will be observed the tubular body is closed at each end by bending the ends *a*⁷ of the portions *a*⁸ forming the bottom of the 40 ruler body upwardly on a curve which extends from the bottom of the scale to the lower side of the top portion *a*, and by locking the upwardly curved part to the portion *a* by bending a lip-like extension *a*⁹ formed 45 on the end of the portion *a* downwardly and inwardly over the end of the curved portion *a*⁷. The edges of the curved portion *a*⁷ and of the beveled portions *a*⁹ fit closely together, and are curved or rounded, as shown at *a*³ 50 in Fig. 1.

This construction forms not only a very effective closure without the necessity for closing inserts or end plugs, such as are utilized in the construction shown in my 55 prior application, but the rounded ends and edges thus formed render the scale more desirable in many respects.

A further very important improvement and feature of my invention embodied in the 60 present construction resides in the finish of the ruler body, and the manner of applying graduations in easily readable form.

In my prior construction, the graduations and characters of the scale were cut into 65 celluloid in the form of strips which I dis-

covered after much experimenting could be cemented to the metal ruler body, if the latter were first provided with a strongly adhering coating of material, such as baked enamel, the intermediate coating being quite 70 essential, as celluloid cannot be cemented to the surface of metal.

By my present invention, I am enabled to dispense with the cemented strips, and secure a finished ruler which is far more satisfactory, both from manufacturing and commercial standpoints. 75

In accordance with my present invention, the graduations and characters are cut directly into a coating *e* which preferably, 80 although not necessarily, covers the entire outer surface of the ruler body. In order that a coating which is applied to the ruler body may serve as the medium for the cut graduations and characters, this coating 85 must have certain properties not possessed by coatings such as enamel, with which metal is usually or commonly coated. In the first place, it must adhere very strongly to the metal; it must be hard and smooth 90 and at the same time have a certain degree of flexibility so that it will not crack when the ruler body is flexed; its cohesive properties must be such that very fine smooth, clean clear lines can be cut therein, and it 95 must be durable and be able to withstand blows and rough usage generally without chipping or breaking.

The coating which I provide on the ruler body consists of pyroxylin which I find can 100 be applied in liquid form evenly to the ruler body, and when hardened answers all the requirements with high efficiency, and at the same time gives the ruler body a very desirable permanent finish and serves as an 105 admirable metal protecting medium.

It will be observed that the coating *e*, because of its strong adherence to the metal, and because of its hardness, resembles an ordinary baked enamel, but it differs essentially from enamel in the respect that it is not brittle, and because fine smooth lines can be cut into the same. It is obvious that a coating of enamel, or any other material having the brittle characteristic of enamel 115 is quite unsuitable for my purpose, for the reason that if graduations were to be cut into the same, the lines would be rough and ragged. In the respect that the cohesive properties of the coating *e* permit fine 120 smooth lines to be cut into the same, the coating partakes of the properties of celluloid, and by reason of these similar characteristics between the coating which I employ and celluloid, the coating may be defined as celluloidal. Celluloid, however, 125 cannot be used for the purpose described herein, for the reason that it will not adhere directly to the metal, regardless of how or in what form it is applied thereto. 130

Preferably, the portions of the coating in which the graduations and characters are cut, viz: the portions which cover the beveled parts a' of the ruler body are white, 5 so that the graduations and designating characters of the ruler will stand out sharply and be easily readable. The other portions of the coating may, however, by suitable coloring matter, be given any desired color or colors.

Having thus described my invention, what I claim is:—

1. A tubular ruler body formed from a strip of sheet metal and having top and bottom walls and one or more ruling edges formed by bending side portions of the strip inwardly with respect to an intermediate portion, the edge portions of the strip being bent inwardly to form an internal rib 20 and being interlocked.

2. In combination in a ruler, a tubular ruler body having top and bottom walls, the end portion of one of said walls being bent at an angle toward the other wall, and the latter having at its end an extension which is folded inwardly over the end of said bent portion.

3. In combination in a ruler, a tubular ruler body having top and bottom walls, the end portion of the bottom wall being inclined upwardly to the top wall and the latter having at its end an extension which is folded downwardly and inwardly over the end of said upwardly inclined portion.

35 4. In combination in a ruler, a tubular ruler body formed from a strip of sheet metal and comprising a top wall and a bottom wall, the latter being formed by bending the side portions of the strip inwardly with respect to the part forming the top wall, the ends of said inwardly bent portions forming the bottom wall being bent upwardly to the top wall, the latter having at its end an extension which is folded downwardly and inwardly over said upwardly bent parts so as to lock the same in place.

45 5. A ruler comprising a metal body provided with a hard strongly adhering coating whose cohesive properties are such that fine smooth lines and characters may be cut in the coating.

6. A ruler comprising a metal body having a strong adhering celluloidal coating in which graduations are cut.

7. A ruler comprising a metal body having a strongly adhering coating of pyroxylin bearing cut graduations.

8. A hollow ruler body formed from a strip of sheet metal, the edge portions of the strip being interlocked on the interior of the body and forming an internal rib extending from one side of the body to the other.

9. A ruler, comprising a metal body, provided with a hard, strongly adhering coating completely enveloping the body and having cohesive properties such that fine smooth graduations may be cut therein.

10. A ruler, comprising a metal body, provided with a hard, strongly adhering and permanently positioned coating enveloping the body, and having cohesive properties such that fine smooth graduations may be cut therein.

11. A ruler, comprising a hollow body having top and bottom walls, the end portion of one of said walls being inclined at an angle toward the other wall, and the latter having at its end a portion which is folded over the end of said inclined portion.

12. A ruler, comprising a metal ruler body completely enveloped in a hard closely adhering medium bearing cut graduations, said medium having cohesive characteristics such that fine graduations and characters may be cut therein.

13. A ruler comprising a metal body completely enveloped in a permanently positioned hard covering in which graduations are cut, said covering having cohesive properties which permit fine, smooth, legible lines to be cut therein.

14. A ruler comprising a metal body entirely surrounded by a covering of pyroxylin bearing cut graduations, said covering being held by the body against substantial shrinkage in any direction.

In testimony whereof, I hereunto affix my signature in the presence of two witnesses.
